(57) **CLAIM**

The ornamental design for the weapon mountable illumination device, as shown and described.

DESCRIPTION

FIG. 1—A front perspective view of the weapon mountable illumination device.

FIG. 2—A side view of the weapon mountable illumination device.

FIG. 3—An opposite side-view of the weapon mountable illumination device.

FIG. 4—A rear view of the weapon mountable illumination device.

FIG. 5—A front view of the weapon mountable illumination device.

FIG. 6—A bottom view of the weapon mountable illumination device; and,

FIG. 7—A top view of the weapon mountable illumination device.

The features shown in broken lines in the various Figures are for illustrating the environmental structure and form no part of the claimed design.
